UNITED STATES PATENT OFFICE.

ALFRED WELLS CASE, OF HIGHLAND PARK, CONNECTICUT.

BEATING-ENGINE.

SPECIFICATION forming part of Letters Patent No. 690,097, dated December 31, 1901.

Application filed August 13, 1901. Serial No. 71,891. (No model.)

To all whom it may concern:

Be it known that I, ALFRED WELLS CASE, a citizen of the United States, residing at Highland Park, in the county of Hartford and 5 State of Connecticut, have invented certain new and useful Improvements in Beater-Engines, of which the following is a specification.

This invention relates to those machines which are built for the purpose of beating 10 and macerating or shredding fibrous material into pulp.

The beater which forms the subject of this invention is particularly designed for beating scrap-leather into pulp, although it may be 15 used for beating other materials.

Scrap-leather contains more or less greasy matter and lumps or bunches which are not easily macerated or shredded. To form good smooth leather-board, the pulp must be uniformly beaten and all bunches and matted portions broken up. With the ordinary beater to insure uniform density and absence of lumps the entire mass must be beaten until all of the stock is completely reduced, al- 25 though, of course, most of the mass will be reduced before the lumps are reduced.

The object of this invention is the production of a beating-engine which is so constructed that the material which is to be beaten can be continuously fed into the tub and the stuff as it is sufficiently beaten can be continuously removed, thus effecting a saving of energy and time, besides insuring a uniform product without nubs.

35 The beater which is illustrated in the accompanying drawings as embodying the invention has a tub with a common vertical mid-feather, bed-plate, backfall, beating-roll, and picker-cylinder, that is partly submerged in the stock in the tub, so as to pick up and throw such stuff as is properly macerated or shredded onto a traveling apron, which transfers the stuff to a stock-vat or other desired receptacle.

45 Figure 1 of the views shows a plan, with the cover removed, of a beating-engine that embodies the invention; and Fig. 2 shows a side elevation, with part in section and the driving-pulleys omitted, of the same engine.

50 The beater illustrated has an oblong tub 1 of ordinary shape and dimensions. In the center of this tub is the usual vertical mid-

feather 2, on one side of which is the bed 3, with bed-plate 4 and the backfall 5 of common design. The posts 6 support the adjustable lighters 7, which carry the bearings that hold the shaft 8. Upon the shaft, over the bed between the mid-feather and one side of the tub, is a common beater-roll 9, and outside of the tub on the shaft is a driving-pulley 10. The lighters are so supported that the periphery of the beater-roll may be adjusted with relation to the blades 11 of the bed-plate beneath the roll, as usual. On a shaft 12, held by bearings secured to the walls 55 of the tub and provided with pulleys 13 and 14, is a cylinder 15. The periphery of this cylinder is arranged to dip into the stuff in the tank and is provided with fine teeth 16, that will pick up fibers from the stuff. 60 On a shaft 17, arranged across the walls parallel with and adjacent to the pick-up-cylinder shaft, is a cylinder 18, that is provided with fine teeth 19, the points of which preferably project between the teeth on the periphery of the pick-up cylinder. On the shaft 17 is a pulley 20, that may be belted to a pulley 21 on the beater-roll shaft, and a pulley 22, that may be belted to the pulley 14 on the pick-up-cylinder shaft, so that the pick-up and 65 break-up cylinders will rotate in the same direction. The teeth on the break-up cylinder break up the matter picked up by the pick-up cylinder and prevent nubs and hard lumps from being carried up and thrown off as the 70 cylinders rotate.

Held by bearings arranged adjacent to the end of the tub are the arbors of rolls 23. One arbor is provided with a pulley 24, which may be belted to the pulley 13 on the pick-up-cylinder shaft, with which these rolls are parallel. An endless apron 25 passes around these rolls. This apron is preferably made of an open-mesh material and is provided with cleats 26. At the outer end of the apron is 75 a stock-tank 27, with a discharge-pipe 28.

The pick-up cylinder is rotated with such speed that it picks up the fine fiber that has been sufficiently beaten and is floating near the surface of the stuff in the tub and throws 80 it onto the traveling apron, which deposits it in the stock-tank. From the stock-tank the properly-beaten stuff may be drawn off 85 through the discharge-pipe to any vat or ma-

chine. Of course the apron could deposit the stuff directly onto the apron of a paper or board machine, and if desired the apron can be dispensed with, in which case the pick-up cylinder can be arranged to deposit stuff directly on a paper-machine apron or into a vat.

A cover 29 is arranged over the pick-up cylinder and inner end of the conveying-apron, so that the material which is thrown by the picker will fall upon the apron. Surplus water which is thrown up with the stuff drains back into the tub. By means of this simple mechanism the stuff which is sufficiently beaten and is free from lumps and bunches is picked up and conveyed to the stock-tank, from which it may be drawn for use. It is unnecessary with this engine to beat the stuff which is completely macerated or shredded until all of the mass is properly reduced, for that which is finished may be taken away as it is completed, leaving only the unreduced part to be beaten. This method results in a large saving of time and energy, for it is not necessary to agitate the part which is finished while the unfinished part is being reduced, and it is not necessary to wait until the unfinished part is reduced before using the stock. Furthermore, the substance to be macerated can be fed in from time to time as the beaten stuff is removed, so that the machine may be run continuously. This is particularly advantageous when beating leather-stock, for the reason that such stock contains hard nubs and greasy lumps, which take much time and power to reduce, and unless the entire mass is reduced evenly the finished product will be imperfect.

I claim as my invention—

1. In combination with the tub of a beating-engine, a pick-up cylinder adapted to be rotated with a part of its periphery submerged in the stock in the tub, and a break-up cylinder located adjacent to the pick-up cylinder, whereby finished stock will be picked up and thrown from the tub and unfinished stock returned to the tub, substantially as specified.

2. In combination with the tub of a beat-

ing-engine, a beater-roll, a pick-up cylinder with fine teeth adapted to be rotated with a portion of its periphery submerged in the stock in the tub, means for rotating the cylinder so that it will pick up and throw off finished stock from the tub, an endless conveyer located with a portion adjacent to the pick-up cylinder and means for moving the conveyer whereby stock deposited upon the conveyer by the pick-up cylinder is conducted away from the tub, substantially as specified.

3. In combination with the tub of a beating-engine, a pick-up cylinder adapted to be rotated with a part of its periphery submerged in the stock in the tub, a break-up cylinder located adjacent to the pick-up cylinder, and a conveyer located adjacent to the pick-up cylinder for conducting away stock which is deposited on it by the pick-up cylinder, substantially as specified.

4. In combination with the tub of a beating-engine, a pick-up cylinder with fine teeth, adapted to be submerged in the stock in the tub, a break-up cylinder with fine teeth, located adjacent to the pick-up cylinder, and an endless conveyer with an end located adjacent to the pick-up cylinder, substantially as specified.

5. In combination with the tub of a beating-engine, a pick-up cylinder with fine teeth, adapted to be submerged in the stock in the tub, a break-up cylinder with fine teeth, located adjacent to the pick-up cylinder, and an endless apron with cleats passing around rolls, one of which is adjacent to the pick-up cylinder, substantially as specified.

6. In combination with the tub of a beating-engine, a pick-up cylinder adapted to be rotated with a part of its periphery submerged in the stock in the tub, and means for rotating the cylinder so that it will pick up and throw off finished stock from the tub, substantially as specified.

ALFRED WELLS CASE.
